UNITED STATES PATENT OFFICE.

ALBERT L. HIGGINS, OF BAR HARBOR, MAINE.

BOTTLE-CAP REMOVER.

1,345,182.

Specification of Letters Patent. Patented June 29, 1920.

Application filed January 23, 1919. Serial No. 272,736.

To all whom it may concern:

Be it known that I, ALBERT L. HIGGINS, a citizen of the United States, residing at Bar Harbor, in the county of Hancock and State of Maine, have invented certain new and useful Improvements in Bottle-Cap Removers; and I do hereby declare the following to be a full, clear, and exact description of the invention, such as will enable others skilled in the art to which it appertains to make and use the same.

My invention relates to improvements in bottle cap removers especially adapted for use in connection with paper disk caps.

An important object of this invention is to provide a milk bottle cap remover having novel means for engaging the cap whereby the device is securely engaged with the cap.

A further object of the invention is to provide a bottle cap remover adapted to be secured to the bottle cap while the bottle to which the cap is attached is in use and having means for partially removing the cap to permit of the dispensing of the contents of the bottle.

A further object of this invention is to provide a bottle cap remover having a relatively wide cap engaging element, whereby slitting of the cap is prevented.

A further object of the invention is to provide a device of the character described, which is simple, reliable and cheap to manufacture.

Other objects and advantages of the invention will be apparent during the course of the following description.

In the accompanying drawing forming a part of this application, and in which like numerals are employed to designate like parts throughout the same,

Figure 1 is a perspective of a device embodied in my invention,

Fig. 2 is a perspective of the device showing the same in use, and

Fig. 3 is a perspective of a slightly modified form of the invention.

In the drawing wherein for the purpose of illustration is shown the preferred embodiment of my invention, the numeral 5 designates a milk bottle having a paper disk cap 6 arranged in the top as usual. A bottle cap remover clearly illustrated in Fig. 1, and generally designated by the numeral 7, is formed from a single blank of metal and comprises an elongated body portion or

lever 8 having an angularly projecting shoulder 9 formed integral with its lower end. The shoulder 9 is provided with a recess 10 formed in its outer edge portion for engaging the periphery of the bottle neck, when the body portion is positioned parallel to the bottle. The plate 8 is bent at an obtuse angle at its upper portion to provide an overhanging shoulder 11. A flange 12 is provided along the outer edge of the shoulder 11 and extends parallel to the body 8. As clearly illustrated in Fig. 2, the flange 12 is adapted for engaging the disk 6 and functioning as a fulcrum for a penetrating point 13. As clearly illustrated in Fig. 1, the penetrating point 13 is provided with a reduced shank 14. The penetrating point 13 is flat and has its longitudinal edges curved outwardly. Upon penetrating a bottle cap, the flat penetrating point 13 will engage the under side of the cap and thereby prevent splitting of the cap and subsequent disengagement of the device with the cap.

The device may be utilized for lifting a portion of the cap by moving the plate or body member 8 about a horizontal axis and thereby bend the cap portion along the line formed by the flange 12. While the bottle is in use, the device may be engaged with the cap and be positioned parallel to the bottle when it is not desired to have the cap partially removed.

In Fig. 3 I have shown a penetrating point 15 similar in construction to the penetrating point 13 of the form shown in Fig. 1. The penetrating point 15 is secured to a handle 16, and is provided with a reduced shank 17. A laterally projecting arm 18 is carried by the handle 16 and is adapted for engaging the bead of the bottle for preventing engagement of the penetrating point with the cap at its center thereof. The handle 16 is provided with an eyelet 19 adapted for securing the device in any convenient place.

The body portion 8 of the form shown in Fig. 1, as the arm 18, is adapted to prevent engagement of the penetrating point with the center of the bottle cap 6. Therefore, the penetrating point of the several forms of the invention will engage the cap at a point adjacent its periphery thereby preventing pushing of the cap into the bottle and the consequent splashing of the contents thereof.

The forward portions of the shanks 14 and 17 have their longitudinal edges provided with concaved notches 20 adapted to receive the edges of the slits caused by the 5 penetrating point 15. Thus on the movement of the levers or handles 8 and 16 about a horizontal axis, the penetrating point will engage the outer adjacent portion of the disk and remove or partly remove the disk 10 as desired.

While I have shown and described the preferred embodiment of my invention, it is understood that I may make such minor changes in arrangement and construction 15 of parts, as will remain within the spirit of the invention and the scope of the appended claims.

Having thus described my invention what I claim is:—

- 20 1. A bottle cap remover including a lever or body member, a shank associated therewith, and an enlarged penetrating point carried by said shank, the forward portion of said shank being provided with concaved notches in its longitudinal edges for receiving the edges of the slit caused by the penetrating member, said lever being adapted to move about a horizontal axis.
- 25 2. A bottle cap remover including a lever or body portion adapted for movement about a horizontal axis, an overhanging shoulder carried by the lever, a shank carried by the shoulder, and an enlarged penetrating point carried by said shank, the forward portion of said shank being provided with concaved notches.
- 30 3. A device of the character described comprising, a body portion, a flange associated with the body portion and extending in spaced parallel relation to the same for functioning as a fulcrum, and a penetrating
- 35
- 40

point carried by said flange, said penetrating point being flat and having its longitudinal edges thereof curved outwardly.

4. A device of the character described 45 comprising, a body portion, a shoulder carried thereby, a flange carried by one edge portion of said shoulder and disposed in parallel relation to said body portion, and a penetrating point carried by said flange 50 and having its longitudinal edges thereof curved outwardly.

5. A device of the character described comprising, a body portion having an upper shoulder provided with a depending 55 flange adapted for engaging a bottle cap, a penetrating point carried by said flange and having its longitudinal edges thereof curved, and a laterally projecting shoulder carried by the lower portion of said body 60 portion and adapted for engaging the periphery of a bottle.

6. A device of the character described comprising, a body portion, a shoulder carried by the upper portion of said body portion and extending at an obtuse angle thereto, a flange carried by said shoulder and disposed in parallel relation with said body portion, a shank carried by said flange, an enlarged penetrating point carried by said 70 flange, and a laterally projecting shoulder extending from the lower portion of said body portion and having a recess therein, said laterally projecting shoulder being adapted for engaging the periphery of a 75 bottle.

In testimony whereof I affix my signature in presence of two witnesses.

ALBERT L. HIGGINS.
